UNITED STATES PATENT OFFICE.

JOHN I. BELLAMY, OF BROOKFIELD, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed December 4, 1924, Serial No. 753,796. Renewed July 27, 1928.

The present invention relates to automatic telephone systems in general, but is concerned more particularly with multi-office automatic telephone systems of the type in which directors are used to register, translate, and retransmit the telephone numbers; and the main object is the production of a new and improved telephone system of the foregoing character in which an intermediate distributing frame is provided common to a plurality of directors. In this respect, this application may be considered an improvement on the co-pending application of Richardson et al., Serial No. 694,482, filed February 25, 1924, and on the co-pending application of Bellamy, Serial No. 746,730, filed October 30, 1924.

As a matter of review, it may be pointed out that a director of the type disclosed herein is employed in a multi-office telephone system primarily to promote trunking efficiency by permitting calls to all offices in the same locality to be handled over the same group of trunks regardless of the numerical designations of the offices, and also in order to promote trunking efficiency by permitting calls to distant offices to be set up step by step through as many intervening tandem offices as may be encountered during the process of trunking the call to the desired office. Specifically, the function of a director of the type disclosed herein is to register the office digits of a number and to transmit in accordance therewith the proper code digits to trunk the call to the desired office in accordance with the most economical trunking arrangement, and to register and retransmit unchanged the four subscriber digits of the number.

As pointed out in the co-pending applications mentioned above, it has been the practice in director systems to provide each director with an intermediate distributing frame upon which there is one group of terminals representing all the contacts in the bank of the office register of that director and another group of terminals representing the ten impulse stop conductors individual to the director. These two groups of terminals are suitably cross-connected in accordance with the trunking arrangement to effect the sending out of the desired code digits in each case. Such an arrangement proves to be entirely satisfactory from the standpoint of regular operation but, in addition to its more or less excessive cost, it proves to be a severe handi-

cap in cases where alterations are made in the trunking arrangement and consequently in the routing of calls, as it is necessary to change the jumpers on the intermediate distributing frame of each and every director. Accordingly, the common intermediate distributing frame has been developed, i. e., circuit arrangements have been made whereby one intermediate distributing frame serves for a plurality of directors, thereby considerably lowering the cost of the installation and facilitating changing the codes on a large number of directors when changes in the trunking layout are made necessary from time to time.

While the present case resembles the two prior cases mentioned in the foregoing in that it shows a director system in which a single distributing frame serves a plurality of directors, entirely different circuit arrangements are used for accomplishing this result, and new principles of operation are followed, as will be pointed out.

According to one feature of the invention, the impulse stop conductors are each maintained at a different electrical potential. Before the transmission of a digit begins, the wiper controlling such digit is connected up to one terminal of the test relay, after having been previously set upon one of the impulse stop conductors, and the other terminal of the test relay is brought into engagement with the impulse stop conductors in order. The test relay is energized from ground before the transmission of the digit and the accompanying testing operation starts, and it energizes upon each succeeding step as long as a potential different from the potential of the pre-selected stop conductor is encountered, but fails to energize when the pre-selected stop conductor is reached, because the same potential is now connected to both of its terminals. The failure of the test relay to respond results in the termination of the digit.

According to a desirable modification of the above arrangement, the test relay is replaced by a polarized test relay which is energized in one direction when the testing operation starts and is energized in the opposite direction to terminate the digit when the next stop conductor beyond the pre-selected one is reached.

Other objects and features have to do mainly with the circuit details involved in carrying out the foregoing. These latter ob-

jects and features will appear fully upon a further perusal of the description.

Referring now to the drawings comprising Figs. 1-10, inclusive, Figs. 1-5, inclusive, 5 show by means of the usual circuit diagrams, a sufficient amount of equipment in a telephone system embodying the principles of the invention to enable the invention to be understood and its utility appreciated; Fig. 6 10 shows a desirable modification of the arrangement shown in Fig. 4 for securing a number of different potentials; and Figs. 7-10, inclusive, show a modification of the embodiment of Figs. 2-5, inclusive.

15 The equipment shown in Fig. 1 comprises the substation A, the individual line switch LS at the exchange, the trunk circuit TC inserted in the trunk leading from the bank to line switch LS to the selector S, and the 20 director selector DS individual to the trunk circuit TC; and the equipment shown in Figs. 2-5, inclusive, comprises one of the directors accessible to the director selector DS, together with the intermediate distributing 25 frame IDF, Fig. 4, which is common to this director and a plurality of others.

Regarding the equipment shown, the substation A is of the usual automatic type having the usual transmitting and receiving instrumentalities and also a calling device for 30 controlling the automatic switches.

The line switch LS is mechanically of the usual rotary type in which the wipers have no normal position and are moved in a forward direction only, being advanced upon the 35 back stroke of the associated stepping magnet rather than upon the forward stroke.

The trunk circuit TC is provided primarily to enable a director to be temporarily associated with the connection, and comprises 40 the usual line, release, and switching relays.

The selector S is an automaite switch of the usual vertical and rotary type having bank contacts arranged in horizontal rows 45 or levels.

The director selector DS is similar to the line switch LS, both as regards its operation and also from a mechanical standpoint.

The sequence switch S, Fig. 2, is a simple 50 step by step switch having wipers 108 and 110 which are advanced in a forward direction by stepping magnet 105 and which are restored to normal position under the control of release magnet 106 whose circuit passes 55 through off normal contacts 107 and is therefore opened when the wipers reach their normal position. This sequence switch distributes the incoming impulse conductor to the various operating magnets of the director, 60 as will hereinafter appear.

The sequence switch S' is, from a mechanical standpoint, similar to the line switch LS and the director selector DS, and its function is to bring about the transmission of the various series of impulses in their proper order. 65

The office register OR, Fig. 4, is, mechanically, an automatic switch of a type similar to the selector S, Fig. 1, and its function is to register the two office digits in any called number, preparatory to the transmission of the necessary code digits to route the call to the desired office. 70

The digit registers DR-1-DR-4, inclusive, are each similar, mechanically, to the sequence switch S, and their function is to register the four subscriber digits of any number. 75

The sending switch S², Fig. 3, is similar, mechanically, to the sequence switch S', and its function is to count off the impulses as they are being transmitted, and to connect the test relay 205 to the various impulse stop conductors in regular order. 80

The intermediate distributing frame IDF is connected between the multiplied bank contacts of the office registers, such as the office register OR, Fig. 4, and the ten impulse stop conductors 241-250, so that the office codes may be readily changed and so that the changing of jumpers at one point changes the office 90 codes of a plurality of directors.

In order to enable the invention to be understood best, the operations accompanying the setting up of a connection from the line of substation A to a called line will now be 95 described. For this purpose it will be assumed that the subscriber at substation A desires to make a call and accordingly removes his receiver.

When the receiver is removed at substation 100 A, a circuit is closed over line conductors 2 and 3 for line relay 6 of the line switch LS. Line relay 6 thereupon energizes and at armature 11 places ground on private normal conductor 4, thereby making the calling 105 line busy and closing a circuit through switching relay 5 and stepping magnet 7 in series. At armature 12, line relay 6 connects test wiper 14 to the junction of switching relay 5 and stepping magnet 7. In case the trunk 110 on which wipers of the line switch are standing is idle, this latter operation does not have any particular utility, and switching relay 5 energizes, seizing the trunk.

Assuming on the other hand that the trunk 115 upon which the wipers of the line switch LS are standing is busy, test wiper 14 is in engagement with a grounded test contact and switching relay 5, being short circuited, does not energize. Stepping magnet 7 in this case 120 energizes from the grounded test wiper 14, and, being self-interrupting, operates in a buzzer-like manner to advance the wipers 13-15, inclusive, step by step in search of an idle trunk. 125

When an idle trunk is reached, which trunk, it will be assumed, is the one comprising conductors 16-18, switching relay 5, being no longer short circuited, energizes in series with stepping magnet 7. Stepping 130

magnet 7 does not operate at this time on account of the high resistance of switching relay 5. Upon energizing, switching relay 5 opens the test circuit and prepares the holding circuit at armature 9; and at armatures 8 and 10 disconnects line conductors 2 and 3 from line relay 6 and the ground and extends them by way of wipers 13 and 15, conductors 16 and 18, and armatures 33 and 35, to the 10 windings of line relay 25 of the trunk circuit TC. Line relay 25 now energizes over the calling loop and closes at armature 28 a circuit for the slow acting release relay 26 which thereupon energizes and places ground 15 upon release trunk conductor 17 at armature 30, thereby completing the usual holding circuit for switching relay 5 of the line switch LS before the slow acting line relay 6 has had time to deenergize.

20 In the trunk circuit TC, as a further result of the energization of release relay 26, a circuit is closed at armature 31 for switching relay 37 and stepping magnet 68 of the director selector DS in series, and test wiper 75 25 is connected at armature 32 to the junction of switching relay 37 and stepping magnet 68. Accordingly, the director selector DS operates in a manner similar to that just described in connection with the line switch LS 30 to select an idle director. When an idle director is reached, switching relay 67 energizes; opens the test circuit and places ground upon test wiper 75 at armature 71, thereby grounding release trunk conductor 79 of the 35 seized director; connects up the operating conductor at armature 72; and at armatures 69 and 70 connects the conductors leading to line relay 41 of the selector S through wipers 73 and 74 to a normally closed bridge in the 40 director including conductors 77 and 78 and armatures 19 and 21 and their resting contacts in multiple. Accordingly, line relay 41 of the selector S energizes and closes at armature 50 a circuit for release relay 42, 45 which energizes also, preparing the selector for operation in the usual manner.

In the seized director, release relay 201 50 energizes over release trunk conductor 79 responsive to the grounding of the said conductor 79 by the director selector DS, as above pointed out, removes ground from the restoring conductors 114 and 233 at armatures 216 and 218; and opens the normal restoring circuit of the sending switch S² at 55 armature 217.

The above operations, it will be remembered, have all taken place responsive to the removal of the receiver at substation A, and the circuits are now in readiness for the first 60 digit in the desired number to be dialled. Accordingly, the subscriber at substation A turns his calling device for the first digit and line relay 25 of the trunk circuit TC is deenergized a corresponding number of times in 65 the usual manner. Upon each deenergiza-

tion, line relay 25 transmits an impulse of current to the director over the following path: from ground by way of the resting contact and armature 29 of line relay 25, armature 72 and its working contact, wiper 76, 70 impulse conductor 80, and series relay 101, Fig. 2, to wiper 110 of the impulse distributing sequence switch S. Wiper 110 is normally in engagement with conductor 121 which leads to the vertical magnet of the office 75 register OR, Fig. 4. Accordingly, the vertical magnet of the office register OR is energized once for each impulse of current transmitted to the director over the operating conductor 8, and the wipers 301—304, are raised 80 step by step and come to rest opposite the desired level of bank contacts. Relay 101, Fig. 2, is energized in series with the vertical magnet of the office register OR upon the first impulse of current being transmitted to 85 the latter, and, being slow acting, maintains its armature attracted through the series of impulses. At armature 103, relay 101 closes a circuit for relay 102 which energizes and prepares at armature 104 a circuit for magnet 105 of the sequence switch S. Accordingly, when series relay 101 deenergizes at the end 90 of the series of impulses, an impulse of current is transmitted to magnet 105 during the interval required for relay 102 to fall 95 back after its circuit is opened. Magnet 105 thereupon energizes and advances wipers 108 and 110 into engagement with the second set of bank contacts.

When the calling subscriber dials the 100 second digit, the resulting impulses are transmitted over the previously traced circuit as far as wiper 110 of the sequence switch S and are then transmitted over conductor 122 to the rotary magnet of the office register OR. That being the case, wipers 301—304, are 105 rotated step by step and come to rest in engagement with the desired set of bank contacts, which contacts, it will be assumed, are the contacts 305—308. Series relay 101 is again energized with the result that the wipers 108 and 110 of the sequence switch S are advanced another step at the end of the 110 rotary movement of the office register OR. Wiper 108, upon coming into engagement with the third associated bank contact, initiates the sending operation, and the sender, Fig. 3, starts to send out the first of the office code digits, as will be subsequently explained.

115 Responsive to the four remaining manipulations of the calling device at substation A, the digits registers DR—1—DR—4, Fig. 5, are operated over conductors 151—154, respectively, the wipers of the sequence switch S being advanced one step at the end of each 120 series of impulses in the hereinbefore described manner.

125 Considering now the office register OR, it will be remembered that the wipers 301—304 are in engagement with the bank contacts 130

305—308, respectively, and it may be pointed out at this point that the subsequent description will show how the wipers 301—304 control the value and number of the code digits 5 in accordance with the jumpering, at the intermediate distributing frame IDF, of the conductors associated with the contacts upon which these wipers are standing. It will be noted that the first contact 305 is connected 10 with the third impulse stop conductor 243 by means of jumper 309; the second contact 306 is connected with the seventh impulse stop conductor 247 by means of the jumper 310; the third contact 307 is connected with 15 the fifth impulse stop conductor 245 by means of the jumper 311; and the fourth contact 308 is not connected to any of the impulse stop conductors, but is left open. Accordingly, as will be described hereinafter, 20 three code digits 3, 7, and 5 will be transmitted, owing to the connections made by the jumpers 309, 310, and 311, respectively, and no digit will be transmitted when wiper 304 is connected up because contact 308 is 25 left dead, and the sequence switch S', Fig. 2, will be advanced automatically past the fourth code-digit position as will herein-after appear.

Returning now to the point at which 30 wipers 108 and 110 are advanced into engagement with the third set of bank contacts immediately following the termination of the rotary movement of the office register OR, Fig. 4, wiper 108 connects the interrupter 109 to the start conductor 116, whereupon impulse relay 202, Fig. 3, commences to energize and deenergize under the control of interrupter 109 in order to transmit the necessary impulses to extend the connection. 35 Upon the first energization of relay 202 following the connecting up of the interrupter 109, armature 220 closes a circuit through the resting contact and armature 228 for stepping magnet 207 of the sending switch 40 S². Stepping magnet 207 thereupon energizes and moves the associated pawl into engagement with the next notch in the wiper-driving ratchet wheel but does not move the wipers 208 and 209. Upon the following 45 deenergization of impulse relay 202, the circuit of stepping magnet 207 is opened at armature 220, whereupon stepping magnet 207 deenergizes and advances the wipers 208 and 209 into engagement with the first set of bank 50 contacts. Wipers 208 and 209 both engage grounded contacts, and pick-up wiper 208 closes a circuit for pick-up relay 203. Upon energizing, pick-up relay 203 removes the shunt from around armature 219 at armature 55 221; closes at armature 222 a circuit from the normally closed contacts controlled by armature 226, through armature 215 and its working contact, and over conductor 114 for stepping magnet 111 of the sequence switch S', which thereupon energizes preparatory to 60 65

advancing the wipers 112 and 113; prepares a locking circuit for stop relay 204 at armature 223; and at armature 224 closes a circuit from armature 220 and its resting contact for the stiffly adjusted circuit-closing relay 206. Relay 206 has a winding which is highly inductive so as to delay the building up of current flow therethrough. Also, this relay is adjusted with very stiff spring tension. These two things combine in making 70 the relay considerably slower than the average relay to pull up. Accordingly, it remains inert for a slight interval after its circuit is closed.

Returning now to wiper 209, this wiper, 80 upon being advanced into engagement with its first associated contact, extends ground through contacts 210 and the resting contact and armature 230 to one terminal of test relay 205. The other terminal of test relay 85 205 is connected through conductor 117, stop conductor control wiper 113 of the sequence switch S', the first code digit stop conductor 141, wiper 301 of the office register OR, bank contacts 305, and jumper 309 of the intermediate distributing frame IDF to the third impulse stop conductor 243. Accordingly, 90 test relay 205, Fig. 3, is energized by the portion of the battery included between conductors 243 and ground, and at armature 231 95 opens a point in the circuit of stop relay 204 just prior to the energization of the stop circuit closing relay 206, thereby preventing the energization of stop relay 204 at this time. Upon energizing, relay 206 tries to close a 100 circuit for stop relay 204 at armature 232, but cannot do so on account of the fact that test relay 205 is energized.

The wipers 208 and 209 of the sending switch S² have now been advanced into their pickup position, and the shunt has been removed from around armature 219 and its resting contact of impulse relay 202 at armature 221 of pick-up relay 203. Accordingly, upon the next energization of impulse relay 202 105 under the control of the interrupter 109, the outgoing control circuit is opened at armature 219; and at armature 220 the circuit of relay 206 is opened and the circuit of stepping magnet 207 of the sequence switch S² is 110 closed. Accordingly, the stiffly adjusted stop-circuit-closing relay 206 quickly falls back, and stepping magnet 207 energizes 115 preparatory to again advancing the wipers 208 and 209. At contacts 210 magnet 207 disconnects wiper 209, thereby bringing about the deenergization of test relay 205. This is done on each step of the switch S² in order 120 that test relay 205 will be in a deenergized condition at the beginning of each testing operation. This insures the stopping of the sending operation at the correct point, as will herein-after appear.

When impulse relay 202 subsequently deenergizes, it again closes the outgoing con- 125 130

trol circuit at armature 219, and at armature 220 opens the circuit of stepping magnet 207 and closes the circuit of relay 206, which does not, however, pull up immediately for the 5 reasons above given. Stepping magnet 207 now deenergizes and advances wipers 208 and 209 another step. Test wiper 209 now engages the first impulse stop conductor 241, and, since this is not the stop conductor to 10 which the other terminals of test relay 205 is connected by means of jumper 309 on the intermediate distributing frame IDF, test relay 205 energizes again and disconnects stop relay 204 at armature 231 just prior to the 15 pulling up of relay 206.

In the same way, impulse relay 202 again energizes and again opens the outgoing control circuit at armature 219, and wipers 208 and 209 are again advanced in the above manner when relay 202 subsequently deenergizes. This time, test relay 205 energizes from the section of the battery included between conductors 242 and 243 and prevents the energization of stop relay 204.

Upon the next energization of impulse relay 202, the third interruption is produced in the outgoing control circuit at armature 219. At armature 220 stepping magnet 207 is energized and at contacts 210 disconnects wiper 209, bringing about the deenergization of test relay 205. When relay 202 then falls back, the outgoing control circuit is closed at armature 219, and at armature 220 the circuit of magnet 207 is opened and the circuit of relay 206 is closed. Upon deenergizing, magnet 207 advances wipers 208 and 209 another step and wiper 209 comes into engagement with the bank contact in which the third impulse stop conductor 243 terminates. Accordingly, test relay 205 is connected to the same conductor at both terminals and does not energize. That being the case, when the stiffly adjusted stop-circuit-closing relay 206 energizes, it closes at armature 232 a circuit 40 through the resting contact and armature 231, normally closed contacts controlled by armature 227, and resistance 234 for stop relay 204. Stop relay 204 now energizes and closes a locking circuit for itself at armature 227 which includes the working contact and armature 228, at the same time opening its initial circuit; disconnects stepping magnet 207 from the working contact of armature 220 at armature 228; places a shunt 50 around armature 219 and its resting contact at armature 225 so as to prevent further interruptions in the outgoing control circuit; shifts the circuit of magnet 111 of the sequence switch S' at armature 226 from ground through the normally closed contacts controlled by armature 226 to ground through the working contact and armature 226, armature 231 and its resting contact, and armature 232 and its working contact; and at 60 armature 230 disconnects test relay 205 from

test wiper 209 and connects it to ground, whereupon relay 205 again energizes and opens the circuit of stepping magnet 111 of the sequence switch S' at armature 231. Magnet 111 now deenergizes and advances the 70 wipers 112 and 113 one step. Wiper 113 shifts the associated terminal of the test relay 205 from the first code-digit stop conductor 141 to the second code-digit stop conductor 142. Test relay 205 remains energized 75 because the second code-digit stop conductor 142 is connected to battery by way of the seventh impulse stop conductor 247 through wiper 302 of the office register OR, bank contacts 306, and jumper 310 on the intermediate 80 distributing frame IDF.

It will be understood that the above operations all occur in quick succession and are completed before impulse relay 202 energizes again to bring about the deenergization 85 of relay 206. Relay 206 continues to energize and deenergize under the control of impulse relay 202 for the time being, but no further results accompany such action.

As a further result of the above energization of stop relay 204, it connects the grounded pick-up wiper 208 at armature 229 through interrupter contacts 211 to stepping magnet 207. Accordingly, stepping magnet 207 operates with a quick vibratory movement and 90 the wipers 208 and 209 are quickly spun around to the position shown in the drawings, the movement being stopped owing to pick-up wiper 208 leaving the last grounded bank contact and arriving upon the dead contact 100 shown. As a further result of pick-up wiper 208 passing off the last grounded contact, the circuit of pick-up relay 203 is opened. This relay does not fall back immediately, however, owing to the fact that it is slow acting. 105

In the selector S, Fig. 1, line relay 41 deenergizes responsive to each of the three interruptions produced in the outgoing control circuit of the director, as above described, and, upon each deenergization, closes at armature 50 a circuit for vertical magnet 66 through armature 52 and its working contact and series relay 43. By the operation of vertical magnet 66, the wipers 60-62, are raised step by step and come to rest opposite the 110 third level of bank contacts. Relay 43 is energized in series with vertical magnet 66, and, being slow acting, maintains its armature attracted throughout the vertical movement. At armature 53, relay 43 closes, in conjunction with off normal contacts 49 which close upon the first vertical step, a circuit through interrupter contacts 87 of rotary magnet 48 for stepping relay 44. Stepping relay 44 accordingly energizes and closes a locking circuit for 115 itself at armature 54, and at armature 55 prepares a circuit for rotary magnet 48. 120

At the end of the vertical movement, slow acting relay 43 deenergizes and closes the 125 rotary magnet circuit at armature 53. Ro- 130

tary magnet 48 now energizes and advances the wipers 60-62 into engagement with the first set of bank contacts in the third level, and, near the end of its stroke, opens at interrupter contact 67 the circuit of stepping relay 44, whereupon stepping relay 44 de-energizes and opens the circuit of stepping magnet 48 at armature 55. Stepping magnet 48 now deenergizes and closes its interrupter contacts 67 again.

The further operation now depends upon whether the trunk terminating the first set of bank contacts is busy or idle. In case this trunk is idle, switching relay 45 energizes, seizing the trunk. Assuming on the other hand that the trunk is busy, switching relay 45, being short circuited by the ground potential encountered on the busy test contact by test wiper 61, does not energize, and stepping relay 44 energizes from this same ground potential and again closes the rotary magnet circuit at armature 55, whereupon rotary magnet 48 energizes again and advances the wipers 60-62 another step.

This alternate operation of stepping relay 44 and rotary magnet 48 continues as described until an idle trunk is reached, which trunk, it will be assumed, is the one comprising conductors 63-65. When rotary magnet 48 falls back and closes its interrupter contacts 67 after having advanced the wipers into engagement with this idle trunk, switching relay 45, being no longer short circuited, energizes from the grounded release trunk conductor 17 through off normal contacts 49, interrupter contacts 67, and stepping relay 44. Stepping relay 44, however, does not energize at this time on account of the high resistance of switching relay 45. Upon energizing, switching relay 45 disconnects ground from armature 50 of line relay 41 at armature 58, thereby opening the circuit of release relay 42; opens the test circuit and prepares the holding circuit at armature 57; and at armatures 66 and 59 disconnects the incoming line conductors from line relay 41 and extends them by way of wipers 60 and 62, the bank contacts with which these wipers are in engagement, and conductors 63 and 65 to the line relay of the selector to which the seized trunk extends. The line and release relays of this selector (not shown) now energize and prepare the switch for operation in the usual manner.

In the director, pick-up relay 203 falls back at the end of the interval for which it is adjusted; places another shunt across conductors 77 and 78 at armature 221; opens a further point in the circuit of stepping magnet 111 of the sequence switch S' at armature 222; disconnects relay 206 at armature 224, whereupon relay 206 stops vibrating; and at armature 223 opens the locking circuit of the slow acting stop relay 204. Accordingly, after the interval for which it is adjusted,

stop relay 204 deenergizes to initiate the transmission of the second code digit 7. It may be pointed out at this time that the interval of time required for relays 203 and 204 to fall back, one after the other, is proportioned so as to give plenty of time for the above described change-over and trunk-hunting operations of the selector S , Fig. 1.

Upon deenergizing, stop relay 204 removes at armature 225 the shunt around contacts 219 and 221; opens a further point in its own locking circuit and prepares its initial energizing circuit again at armature 227; shifts the working contact of armature 222 of relay 203 back to ground again at armature 226; opens a point in the restoring circuit of the switch S' at armature 229; shifts the left hand terminal of test relay 205 from ground back to wiper 209 through contacts 210 at armature 230, whereupon relay 205 deenergizes; and at armature 228 places stepping magnet 207 under the control of armature 220 of impulse relay 202 again. Accordingly, stepping magnet 207 starts to energize and de-energize again under the control of impulse relay 202 and the second code digit is transmitted in the same way as the first, the difference being that the right hand terminal of test relay 205 is now connected by stop conductor control wiper 113 of the sequence switch S' over the second code-digit stop conductor 142, wiper 302, bank contacts 306, and jumper 310 to the seventh impulse stop conductor 247 instead of over conductor 141 to the third impulse stop conductor 243, as in the previous case. Therefore, it will be at once appreciated that, as the counting switch S' continues to advance from contact to contact, test relay 205 will continue to energize upon each step until wiper 209 arrives upon the bank contact in which the seventh impulse stop conductor 247 terminates, and that when this contact is reached, test relay 205 fails to pull as was the case in the preceding example when the contacts associated with the third impulse stop conductor 243 was reached. The failure of test relay 205 to pull up at this time results in the energization of stop relay 204 with the hereinbefore described results. Accordingly, the second code digit 7 is terminated and the sequence switch S' is advanced one step.

Responsive to the transmission of the second code digit 7, the selector to which the trunk comprising conductors 63-65, inclusive, Fig. 1, extends, raises its wipers opposite the seventh level of bank contacts and selects an idle trunk in the usual manner.

In the director, pick-up relay 203 deenergizes after an interval and its deenergization is followed by the subsequent deenergization of stop relay 204 and the transmission of the third and last code digit 5 begins. Since wiper 113 of the sequence switch S' is now standing on the third associated bank con-

tact, the right hand terminal of test relay 205 is connected through the third code-digit stop conductor 143, wiper 303, bank contact 307, and jumper 311 to the fifth impulse stop conductor 245. The transmission of the third code digits proceeds in the same manner as the transmission of either of the first two digits until wiper 209 of the sequence switch S^2 arrives upon the bank contact in which the fifth impulse stop conductor 245 terminates, and, when this contact is reached, no circuit is closed for relay 205 because both terminals are connected to the same conductor, and stop relay 204 energizes with the hereinbefore described results. This time, as before, when the left hand terminal of relay 205 is connected to ground by armature 230, test relay 205 energizes again and opens the circuit of stepping magnet 111 of the sequence switch S' at armature 231. Accordingly, magnet 111 deenergizes and the wipers 112 and 113 are advanced another step. Stop conductor control wiper 113 connects the right hand terminal of test relay 205 through the fourth code digit stop conductor 144 and wiper 304 of the office register OR to the dead contact 308. Accordingly, test relay 205 now deenergizes and at armature 231 closes a point in the circuit of stepping magnet 111 of the sequence switch S' . As far as the ultimate result is concerned, it is immaterial whether the stop circuit closing relay 206 has fallen back by this time or not, but, assuming that it has, stepping magnet 111 does not energizes at this time, but it energizes again as soon as relay 206 pulls up again and completes the circuit at armature 232. When relay 206 again deenergizes, magnet 111 deenergizes and advances the wipers 112 and 113 another step. Wiper 113 is now in engagement with the first subscriber-digit stop conductor 151 which extends to the wiper 401 of the digit register DR-1. Accordingly, test relay 205 now energizes again over conductor 151 and opens a point in the circuit of stepping magnet 111 at armature 231 to prevent the further advance of the sequence switch S' at this time. It may be pointed out that a circuit will be closed for test relay 205 over conductor 151 and wiper 401 at this time, regardless of the position of wiper 401. For example, if wiper 401 is still in its normal position due to the fact that the calling subscriber has not yet dialled the first subscriber digit, test relay 205 energizes due to battery supplied through stop relay 204 and conductor 260, the resistance 234 being inserted in the locking circuit of relay 204 to prevent relay 205 from being short circuited at this time by the locking circuit of relay 204. It will now be seen that stop relay 204 will be held energized in series with test relay 205 even after relay 203 deenergizes and opens the locking circuit of stop relay 204 at armature 243, and that stop relay 204 will be main-

tained energized to prevent the starting of the transmission of the first subscriber digit until after wiper 401 moves off its normal contact when the dialling of the first digit finally begins. In the same way, the transmission of each of the other subscriber digits is delayed until after the dialling of such digits has begun, in case the digit is not completely dialled before the sequence switch S' arrives in the corresponding position.

If, on the other hand, the first subscriber digit has been dialled, wiper 401 is standing on one of its other contacts and relay 205 is energized from one of the stop conductors 241-250.

It will now be seen that the code digits 3, 7, and 5 have been transmitted and that the fourth code digit position has been skipped by the sequence switch S' because no jumper is connected to the fourth contact of the set in use on the intermediate distributing frame. It will, of course, be apparent that, in case the occasion arises, as many code digit positions as desired may be skipped. In fact, all code digits are automatically skipped in case all four jumpers are omitted, the operation being similar to the operation occurring during the transmission of the digits, with the exception that stop relay 204 is energized right away to place a shunt around armature 219 and its resting contact at armature 225 and prevents any interruption in the outgoing control circuit.

Responsive to the transmission of the third code 5, the selector switch seized in response to the transmission of the second code digit 7, raises its wipers opposite the fifth level of bank contacts and selects a trunk line leading to the desired office.

In the director, as soon as relays 203 and 204 have both fallen back, the transmission of the first subscriber digit begins. The transmission of this digit continues as long as test relay 205 continues to energize over wiper 401, but when wiper 209 of the sending switch S^2 arrives upon the stop conductor on which wiper 401 is standing, relay 205 fails to pull and the digit is terminated in the usual manner.

The sequence switch S' , of course, advances another step and wiper 113 connects test relay 205 to the second subscriber-digit stop conductor 152 and the second subscriber digit is accordingly transmitted in accordance with the setting of wiper 402 of the digit register DR-2.

In the same way, the sequence switch S' is again advanced, and the third subscriber digit is controlled over stop conductor 153 and wiper 403 of the digit register DR-3. Similarly, the fourth subscriber digit is controlled over the fourth subscriber-digit stop conductor 154 and wiper 404 of the digit register DR-4.

The sequence switch S' again advances

upon the termination of the fourth subscriber digit, and wiper 113 passes from the bank contact associated with the fourth subscriber digit stop conductor 154 and lands upon bank contact 118 in which the combined operating and switching conductor 80 terminates. Test relay 205 now energizes over wiper 113, bank contact 118, conductor 80, wiper 76 of the director selector DS, working contact and 10 armature 72, armature 29 and its working contact, and switching relay 27. Switching relay 27 now energizes and closes at armature 34 a locking circuit for itself. As a further result of the energization of relay 27, 15 it disconnects conductors 16 and 18 at armatures 33 and 35 and extends them to the corresponding conductors leading to the selector S, at the same time disconnecting the line conductors of the selector S from the control 20 bridge of the director, leaving the established connection under the direct control of the calling subscriber. Line relay 25 deenergizes upon being disconnected and at armature 29 disconnects the combined switching 25 and operating conductor from switching relay 27 and connects it to ground. At armature 28, relay 25 opens the circuit of release relay 26 which subsequently deenergizes; removes ground from release trunk conductor 30 17 at armature 30, leaving the connection held up by the ground supplied over release trunk conductor 64 of the trunk comprising conductors 63—65; opens another point in the 35 previously closed test circuit of the director selector DS at armature 32; and at armature 31 opens the circuit of switching relay 67 of the director selector DS, whereupon relay 67 deenergizes and disconnects the associated wipers.

40 In the director, test relay 205 is short circuited upon the above mentioned closure of the locking circuit of switching relay 27 of the trunk circuit TC, and thereupon falls back, permitting at armature 231 the circuit 45 of stepping magnet 111 of the sequence switch S' to be closed at armature 232 of relay 206. This results in the wipers 112 and 113 taking another step, whereupon wiper 113 picks up battery and test relay 205 energizes again, preventing the sequence switch S' from advancing further at this time.

When the wipers of the director selector DS are disconnected by relay 57, as above 55 pointed out, ground is removed from release trunk conductor 79, whereupon release relay 201 of the director deenergizes; disconnects conductor 114 from the sending circuit at armature 215; closes the normal restoring circuit of the sequence switch S' at armature 60 216; closes the normal restoring circuit of the sending switch S² at armature 217; and at armature 218 places ground on conductor 233 in order to release the sequence switch S, the office register OR, and the subscriber-digit registers DR—1—DR—4. The release 65

of the sequence switch S is brought about upon the energization of release magnet 106 through off normal contacts 107, and the circuit of release magnet 106 is opened at off normal contacts 107 when the wipers 108 and 110 reach their normal position. The release of the other switches over conductor 233 occurs in the same manner. It may be pointed out that the closure of the normal restoring circuit of the sending switch S² at 75 armature 217 does not have any particular utility in this present case because the said sending switch S² is already in its normal position but is of utility in cases where the calling subscriber replaces his receiver while the sending switch is in an off normal position. Responsive to the closure of the normal restoring circuit of the sequence switch S' at armature 216, stepping magnet 111 operates over conductor 115 and through wiper 112 80 and advances the wipers the remaining step to their normal position because it interrupts its own circuit in this case.

About the only other point that need be mentioned at this time in connection with the restoration of the director, is that pick-up relay 203 deenergizes probably at about the same time that the release relay of the trunk circuit TC falls back and that stop relay 204 deenergizes shortly thereafter. The director is now in its normal condition and is ready to be used in handling another call.

Regarding the desired connection, it may be pointed out that a thousands selector, a hundreds selector, and a connector in the 100 called office, have been operated responsive to the transmission of the fourth subscriber digits of the number to extend the connection to the desired line, and that, in case the called line is idle, the desired subscriber's bell is being rung in the usual manner.

When the called man answers the ringing current is disconnected and the talking circuit is closed. The two subscribers now converse.

When the receiver is replaced at the substation A upon the termination of the conversation, the ground potential is removed in the usual manner, from release trunk conductor 64 of the trunk comprising conductors 115 63—65, whereupon switching relay 45 of the selector S, switching relay 27 of the trunk circuit TC, and switching relay 5 of the line switch LS deenergize. The deenergization of relays 5 and 27 restores conditions in the 120 respective circuits to normal. The deenergization of switching relay 45 of the selector S results in the closure at armature 58 of a circuit through armatures 50 and 52 and off normal contacts 47 for release magnet 46. Release magnet 46 energizes and restores the wipers 60—62 to their normal position, whereupon the circuit of the release magnet is opened at off normal contacts 47.

Referring now to Fig. 6, this drawing 130

shows an alternative arrangement for supplying the necessary potentials to conductors 241-250, Fig. 4. The potential supplied to conductor 250 is, as before, the full battery potential, while the potentials supplied to conductors 241-249 are derived potentials and differ from each other by the amount of drop across the associated resistances. This arrangement is especially recommended 10 for the use in situations where it is impractical or undesirable to tap the exchange battery. The total resistance across the battery will, of course, depend upon the number of directors using the common intermediate distributing frame, and the larger the number, the lower the resistances must be made in order to avoid excessive unbalancing due to the connection of the test relays, such as test relay 205, Fig. 3, across the impulse stop conductors during the testing operations of the various directors.

Referring now particularly to Figs. 7-10, these drawings should be substituted for Figs. 2-5. They show a director similar to the one shown in Figs. 2-5, in that a common intermediate distributing frame is provided. The principal difference lies in the testing arrangement provided for terminating the digits. In this case, a polarized relay is used 30 which does not respond to current flow in one direction and accordingly, it fails to operate until a given conductor is reached and is passed by the test wiper of the sending switch, whereupon it operates due to the reversed current to close a circuit for the stop relay.

Assuming now that the director shown in Figs. 2-5 is disconnected from conductors 77-80; that the director shown in Figs. 7-10 is connected to these same conductors; and 40 that the latter director is seized by the director selector DS, Fig. 1, by way of conductors 77-80, release relay 502, Fig. 8, energizes over conductor 79; removes ground from the restoring contacts in the bank of the upper wiper of the sequence switch S⁴ at armatures 510 and 511; and at armature 512 opens up the release circuit of the register switches and of 45 the sequence switch S³, Fig. 7. The setting of the register switches of this director proceeds in the manner hereinbefore described, and the upper wiper of the sequence switch S³ connects the interrupter 531 to conductor 532 as soon as the office register OR', Fig. 9, is set.

55 It will be assumed that the office register OR' is set upon the contact set shown in the drawings. It will be noted that the first contact is cross-connected to the first impulse stop conductor 541; the second contact is cross connected to the sixth impulse stop conductor 546; the third contact is cross connected to the tenth impulse stop conductor 550; and the fourth contact is cross connected to the skip conductor 560. It will now be explained how 60 this cross connection effects the sending out of

the office code "160" and effects also the skipping of the fourth code digit position.

When the interrupter 531 is connected up to conductor 532, the stepping magnet of the sending switch S⁵ commences to energize and 70 deenergize through the resting contact and armature 519 of stop relay 504, and the wipers 506 and 507 are advanced step by step. Upon the first step of wipers 506 and 507, wiper 506 comes into engagement with a grounded 75 contact and closes the circuit of pick-up relay 503. Relay 503 now energizes and at armature 516 connects the stop conductor distributing wiper of the sequence switch S⁴, Fig. 7, at armature 516 to the polarized test relay 80 505 through armature 520 and its resting contact. This, however, cannot produce any result at this time, because wiper 507 is on a dead contact. As a further result of the energization of pick-up relay 503, it closes at 85 armature 514 a circuit through armature 518 and its resting contact for the stepping magnet of the sequence switch S⁴, which thereupon energizes preparatory to advancing its wipers. Relay 503 also removes the shunt 90 from around the sending contacts of the magnet of the sequence switch S⁵ at armature 513.

The circuits are now in condition for the outgoing control circuit over conductors 77 and 78 to be opened at the right hand contacts of the stepping magnet of the sending switch S⁵. Accordingly, upon the next energization of the said stepping magnet, the outgoing control circuit is opened, and, upon the following deenergization, the outgoing 100 control circuit is again closed and wipers 506 and 507 advance another step. At this time, wiper 507 engages its second contact which is connected with conductor 542, the remaining contacts in bank of wiper 507 being connected 105 in order to conductors 543-551, inclusive. With wiper 507 standing on conductor 542, the polarized relay 505 is included in the following circuit: from ground by way of conductor 541, Fig. 1, the associated jumper, first contact in the selected set in the bank of the office register OR', first wiper of the office register, first contact in the bank of the lower wiper of the sequence switch S⁴, the said 110 lower wiper, the associated conductor, armature 516 and its working contact, armature 520 and its resting contact, relay 505, wiper 507, and conductor 542 to the first section of the tapped battery. The current flow 115 through test relay 505, at this time, is in the right direction to operate it. Consequently, relay 505 energizes and closes a circuit for stop relay 504. Stop relay 504 now energizes 120 and places a short across conductors 77 and 78 at armature 517, thereby terminating the first digit 1. At armature 518, relay 504 opens the circuit of the stepping magnet of the sequence switch S⁴ to permit this magnet to deenergize and advance the associated 125 wipers. At the working contact of armature 130

518 relay 504 closes a locking circuit for itself. At armature 520 relay 504 disconnects the lower wiper of the sequence switch S^4 from test relay 505 and connects it instead to 5 the skip relay 501. This relay, however, is marginally adjusted and does not energize at this time on account of the comparatively low voltage connected to the lower wiper of the sequence switch S^4 . As a further result of 10 the energization of relay 504, it disconnects the stepping magnet of the sending switch S^5 from conductor 532 and connects it through the local interrupter contacts to wiper 506. Accordingly, the wipers 506 and 507 are 15 quickly spun to their normal position in the hereinbefore described manner.

When wiper 506 reaches its normal position, the automatic rotation ceases and the circuit of pick-up relay 503 is opened. Pick-up relay 503 deenergizes after a short interval 20 and places the usual shunt across the impulse circuit at armature 513, and at armature 514 opens the locking circuit of stop relay 504 with the result that relay 504 deenergizes 25 shortly thereafter.

When relay 504 deenergizes, the sending switch S^5 is started in operation for the transmission of the second code digit 6. The lower wiper of the sequence switch S^4 is now standing on its second bank contact and is connected accordingly through the second wiper of the office register OR, and the jumper associated with the bank contact on which this wiper is standing, to the sixth impulse stop conductor 546. Accordingly, when wiper 507 comes into engagement with the first live contact after the transmission of the first impulse in the second code digit, a circuit is closed for test relay 505 through the section 30 of the tapped battery included between conductors 542 and 546. Relay 505, however, does not close a circuit for stop relay 504 at this time, because its armature is attracted in the direction opposite to that in which it 35 must be attracted in order to come into engagement with the associated contact. The same thing is true upon each of the following steps of the sending switch until wiper 507 lands on the bank contact in which conductor 546 terminates, at which time there is no battery included in the circuit of relay 505, and it obviously cannot energize in this case either. As soon, however, as wiper 507 lands on the bank contact in which conductor 40 547 terminates, which it does only after six interruptions in the outgoing control circuit have been produced, a circuit is closed through test relay 505 which includes the section of the tapped battery between the conductors 546 and 547. Accordingly, relay 505 energizes and terminates the second digit in the same manner as described in connection with the termination of the first digit.

From the foregoing, it may be seen that 45 the third code digit to be transmitted is the

digit 0, and that in this case, the polarized test relay 505 does not receive current in the proper direction to close its contact until test wiper 507 of the sending switch S^5 arrives upon the last live contact in its bank, 70 which is the one with which conductor 551 is associated. At this time, since the lower wiper of the sequence switch S^4 is standing on the third bank contact, relay 505 energizes through the portion of the tapped battery included between conductors 550 and 551, thereby terminating the third code digit in the hereinbefore described manner.

The sequence switch S^4 is advanced at this time in the usual manner and its wipers arrive upon the fourth set of bank contacts. The lower wiper is now connected with the fourth wiper on the office register OR. Since all the code digits have been transmitted, it is now desired to cause the sequence switch S^4 to skip the fourth digit position. Accordingly, the fourth contact in the set shown in the bank of the office register OR' is connected by means of a jumper to the skip conductor 560. This conductor is maintained at a 80 much higher potential than any of the other conductors, with the result that the marginal skip control relay 501, Fig. 8, energizes through the working contact and armature 520, working contact and armature 516, 85 lower wiper and fourth contact of the sequence switch S^4 , fourth wiper of the office register OR', the contact upon which it is standing, the associated jumper, skip conductor 560, and the entire battery. Upon 90 energizing, relay 501 connects ground to the second, third, and fourth contacts in the bank of the upper wiper of the sequence switch S^4 , with the result that this switch is automatically advanced from the fourth position 95 to the fifth position. The advance of the wipers of the sequence switch S^4 stops when the fifth position is reached and relay 501 deenergizes.

It is thought that with the foregoing description in mind, the operation of the director in transmitting the four subscriber digits will be readily understood. Briefly, it may be pointed out that the various contacts in the banks of the digit registers are connected in multiple with the corresponding contacts on the left hand side of the intermediate distributing frame IDF, and that the normal contacts of the registers are all multiplied together and connected to stop relay 504, Fig. 8, so as to hold this relay energized to prevent the starting of the transmission of a given subscriber digit until the corresponding register moves off normal.

When the wipers of the sequence switch S^4 125 are advanced one step at the end of the transmission of the fourth subscriber digit, the lower wiper of the sequence switch comes into engagement with the bank contact in which conductor 80 terminates, thereby supplying 130

ground through relay 501, working contact and armature 520, and the working contact and armature 516 to conductor 80 to operate switching relay 27 of the trunk circuit TC, 5 with the result that the connection is switched through as hereinbefore described. The sequence switch S⁴ remains in this condition until release relay 502 deenergizes responsive to the removal of the ground potential from 10 release trunk conductor 79, which occurs in the hereinbefore described manner. Responsive to the deenergization of release relay 502, all the switches of the director are restored to normal position in the usual manner. 15

It may be pointed out now that, since the second, third, and fourth contacts in the bank of the upper wiper of the sequence switch S⁴ are grounded at armature 508 of relay 501 20 when the said relay 501 energizes, the sequence switch S⁴ can be made to advance automatically past any one of its code-digit positions, barring the first, by merely connecting the corresponding bank contacts to the skip conductor 560.

Another point not mentioned hereinbefore is that armature 515 of pick-up relay 503 is provided to maintain release relay 502 energized and to maintain the director guarded 30 as long as the sending switch S⁵ is in an off normal position. This is done in lieu of providing a normal restoring circuit for the sender, and, in case a calling subscriber hangs up during the transmission of a digit, the 35 director will be held engaged until such transmission is finished and until the sending switch restores to normal and pick-up relay 503 deenergizes.

What is claimed is:

40 1. In a telephone system, automatic switches for extending connections from calling lines in one office to called lines in other offices, directors in the first office for controlling said switches, a sender for each director having bank contacts, multiple connections between the bank contacts of all said senders, and means for controlling any sender over said multiple connections.

50 2. In a telephone system, automatic switches for extending connections from calling lines in one office to called lines in another office, directors in the first office for controlling said switches, an office register for each director, sets of bank contacts for said registers multiplied together, a sender for each director, bank contacts for said senders multiplied together, and a distributing frame having sets of contacts on one side thereof connected in multiple with the banks of said 55 registers and having sets of contacts on the other side thereof connected in multiple with the banks of said senders.

60 3. In a telephone system, a call director including a register and a sender, said register and sender each having a wiper and bank of

contacts, multiple conductors extending between the bank contacts of said register and said sender, a test relay having two terminals connected, respectively, to the said wipers, means for setting the wiper of said register 70 upon a desired contact to predetermine a digit, means for operating said sender to transmit impulses and to advance its wiper as said impulses are being sent, and means controlled by said test relay responsive to the 75 operation of said sender for terminating the transmission of impulses in accordance with the setting of said register.

4. In combination, a plurality of control conductors each maintained at an electrical potential different from any of the others, a test relay having two terminals, registering means for bringing one of said terminals in engagement with one of said conductors, and counting means for bringing the other terminal of said test relay into engagement with 85 said conductors successively.

5. In combination, a plurality of control conductors each maintained at an electrical potential different from any of the others, a polarized test relay having two terminals, registering means for bringing any one of said terminals into engagement with one of said conductors, and counting means for bringing the other terminal of said test relay 90 into engagement with said conductors successively.

6. In a call director, a sequence switch having a plurality of positions, a registering device for each of said positions, means for positioning said registering devices on separate contacts, jumpers connected to certain of said contacts, means for transmitting a series of impulses in each position of said sequence switch which corresponds to a registering device positioned on a contact to which a jumper is connected, and means responsive to the omission of the jumper from any one of said contacts for causing the said sequence switch to automatically skip the position which corresponds to the registering device positioned on such contact. 100

7. In a director, a sending-control sequence switch having a control wiper and a restoring wiper, a bank of contacts for each wiper, a relay and means for connecting it to said control wiper, a source of current connected to one of the contacts in the bank of said control wiper for energizing said relay, and contacts on said relay for grounding certain contacts 115 in the bank of said restoring wiper to automatically advance both wipers beyond a predetermined position.

8. In an automatic telephone system, directors for controlling the automatic switches, a sender in each director including a counting device, a distributing frame common to said directors, contacts in each counting device connected in multiple with terminals on one side of said frame, means in each counting 120 125 130

device for successively connecting up the associated contacts, and a register in each director for associating the associated connecting means with a plurality of terminals on the 5 other side of said frame.

9. In an automatic telephone system, directors for controlling the automatic switches, a sender in each director including a counting device, a distributing frame common to said 10 directors, contacts in each counting device connected in multiple with terminals on one side of said frame, a relay in each director for determining the number of impulses in each series transmitted, means in each counting device 15 vice for connecting one terminal of said relay to the associated contacts successively, a register in each director for selecting a plurality of terminals on the other side of said frame, and means in each director for connecting the 20 other terminal of the associated relay to said selected terminals in succession.

10. In an automatic telephone system, a director for controlling the automatic switches, a distributing frame common to said director, 25 and other similar directors, a register in said first mentioned director for selecting a set of terminals on said frame, a counting device in said director, and a sender controlled through the selected terminals by said counting device 30 to transmit a plurality of series of impulses while the register remains in its set position.

11. In an automatic telephone system, a director for controlling the automatic switches, a distributing frame common to said directors, 35 and other similar directors, a register in said director, a sender in said director including a counting device, a relay in said director for determining the number of impulses transmitted by said sender, and a circuit for said relay completed by the counting device and extending through the said register and the said frame.

12. In an automatic telephone system, a director for controlling the automatic switches, 45 a distributing frame common to said director and other similar directors, a sender in said first mentioned director, a register in said director having a plurality of wipers for selecting a set of terminals on said frame, a sequence switch for placing the said sender under the control of each of said wipers in turn, and a counting device in said director cooperating with the said register to control said sender.

55 13. In a director for automatic telephone systems, a source of current, a plurality of taps leading away from said source, each having a different potential, a test conductor, means including a register for connecting one 60 end of said conductor to one of said taps, means including a counting device for connecting the other end of said conductor to all said taps in succession, and a test relay included in said conductor and energized over 65 each of said taps in turn while the counting

device is operating until both ends of said conductor are connected to the same tap.

14. In a director for automatic telephone systems, a source of current, a plurality of taps leading away from said source, each having a different potential, a test conductor, means including a register for connecting one end of said conductor to one of said taps, means including a counting device for connecting the other end of said conductor to all said taps in succession, and a polar relay included in said conductor responsive when the current in said conductor is reversed by the continued operation of said counting device. 70

15. In a director for automatic telephone systems, a register for recording a digit in a called number, a sender for transmitting a series of impulses, and means including a polarized relay for terminating said series of impulses in accordance with the setting of 85 said register.

16. In a director for automatic telephone systems, a register for recording a digit in a called number, a sender for transmitting a series of impulses, a polarized relay for terminating said series of impulses, and means including a counting device for operating said relay at a point determined by the setting of 90 said register.

17. An automatic telephone system including directors in which each director has an office register and a sender directly controlled through the office register wipers by suitable cross-connections on a frame common to all 95 the directors.

18. An automatic telephone system including directors in which each director has a register and a sender and means for stopping a series of impulses, controlled after the series has started, through a wiper of the register by suitable cross-connection on a frame common to 100 said directors.

19. In a telephone system, automatic switches for setting up telephone connections, a plurality of directors for controlling said switches, an impulse sender in each director, and a common set of digit-control conductors multiplied into each of said senders. 110

20. In a call director system including a plurality of call directors, an impulse sender in each director, a register in each director for controlling the associated sender, and common digit control conductors connecting all of said registers and said senders together. 115

21. In a call director system, a call director, a plurality of other call directors, a register and a sender in the first named call director, digit control conductors common to all said call directors multiplied to said register and to said sender, and an individual test circuit controlled jointly by said register and said sender. 125

22. In a call director system, a call director, a plurality of other call directors, a register and a sender in the first named call di- 130

rector, digit control conductors common to all said call directors multiplied to said register and to said sender, and an individual test conductor extending between said register 5 and said sender.

23. In a call director system, a call director, a plurality of other call directors, a register and a sender in the first named call director, digit control conductors common to all 10 said call directors multiplied to said register and to said sender, and testing means controlled jointly by said register and said sender over said common conductors.

24. In a call director system, a call director, a plurality of other call directors, a register and a sender in the first named call director, digit control conductors common to all 15 said call directors multiplied to said register and to said sender, and testing means individual to said register and said sender controlled by the two jointly over said common conductors.

25. In a telephone system, a plurality of call directors each including a register and a 20 sender, digit-control conductors multiplied into all of said registers, other digit control conductors multiplied into all of said senders, and means including a distributing frame for connecting the first multiple of control 25 conductors with the second multiple of control conductors.

26. In a telephone system, a plurality of call directors each including a first register, a second register, and a sender, digit-control 30 conductors connecting all of said senders and all of said second registers together, other conductors connecting all of said first registers together, and means including a distributing frame for suitably connecting said 35 other conductors to said control conductors.

27. In an impulse sender, a plurality of conductors each maintained at a different potential, means including a register for pre-selecting one of said conductors, means for 40 starting said sender to transmit impulses and for associating it with said conductors one after the other, and means for stopping the transmission of impulses responsive to the association of said sender with said pre-selected conductor.

28. In an impulse sender, a plurality of conductors each maintained at a different potential, means including a register for preselecting one of said conductors, means for starting said sender to transmit impulses and for associating it with said conductors one after the other, and means for stopping the transmission of impulses responsive to the association of said sender with the first conductor 50 encountered following the encountering of said preselected conductor.

29. In a director, a register, a sender including a counting device, means for setting the register, means for starting the counting 55 device, a polar relay for stopping the count-

ing operation, and circuit connections such that current flows through said relay while said device is operating and is reversed to operate the relay when the counting device has operated to an extent corresponding to 70 the setting of said register.

30. In a director, a register, a sender including a counting device, means for setting the register, means for starting the counting device, a polar relay for stopping the 75 counting operation, means for supplying current to said relay while the counting device is operating, and means for reversing the flow of current to operate said relay when the operated position of the counting device corresponds to the setting of said register. 80

31. In a director, a register, a sender, means for setting the register, means for starting the sender, a circuit, means including a counting device for varying said circuit 85 through a plurality of stages, one of which corresponds to the setting of said register, and means in said circuit responsive when said particular stage is reached for stopping the sending operation. 90

32. In a director, a register, a sender, means for setting the register, means for starting the sender, a circuit, means for supplying current to said circuit, means including a counting device for stopping the flow 95 of current when the sending operation has proceeded to a point corresponding to the setting of said register, and means controlled over said circuit for stopping the sending operation. 100

33. In a director, a register, a sender, means for setting the register, means for starting the sender, a circuit, means for supplying current to said circuit, means including a counting device for reversing the flow 105 of current when the sending operation has proceeded to a point corresponding to the setting of said register, and means controlled over said circuit for stopping the sending operation. 110

34. The method of governing the number of impulses in a series which consists in pre-determining the one of a plurality of potentials which corresponds to the desired number of impulses, in applying said potentials 115 successively as the respective impulses are generated, and in stopping the transmission of impulses when the predetermined potential is applied.

35. A device for controlling the extent of 120 movement of automatic switching apparatus which comprises two conductors, means including a registering device for placing the one of a plurality of potentials on the first conductor which corresponds to the desired 125 extent of movement, means for progressively increasing the potential on the second conductor as the movement takes place, and means including a testing device operative to stop the movement when the potential on 130

the second conductor is increased until it bears a predetermined relationship to the potential placed on the first conductor.

36. A device for controlling the extent of movement of automatic switching apparatus which comprises two conductors, means including a registering device for placing the one of a plurality of potentials on the first conductor which corresponds to the desired extent of movement, means for progressively increasing the potential on the second conductor as the movement takes place, and means including a testing device operative to stop the movement only after the potential on the second conductor is increased until it bears a predetermined relationship to the potential placed on the first conductor.

37. A device for controlling the extent of movement of automatic switching apparatus which comprises two conductors, means including a registering device for placing the one of a plurality of potentials on the first conductor which corresponds to the desired extent of movement, means for progressively increasing the potential on the second conductor as the movement takes place, and means including a testing device operative to stop the movement only after the potential on the second conductor is increased until it equals the potential placed on the first conductor.

38. A device for controlling the extent of

movement of automatic switching apparatus which comprises two conductors, means including a registering device for placing the one of a plurality of potentials on the first conductor which corresponds to the desired extent of movement, means for progressively increasing the potential on the second conductor as the movement takes place, and means including a testing device operative to stop the movement when the potential on the second conductor is increased to an amount dependent upon the potential placed on the first conductor.

39. A combination for controlling the number of impulses in a series of impulses including a first conductor and a second conductor, means for placing the one of a plurality of potentials on the first conductor which corresponds to the number of impulses in a series, means for progressively increasing the potential on the second conductor as the impulses are generated, and testing means for stopping the impulse series when the potential on the second conductor has been increased until it bears a predetermined relationship to the potential placed on the first conductor.

In witness whereof, I hereunto subscribe my name this 1st day of December, A. D. 1924.

JOHN I. BELLAMY.
